UNITED STATES PATENT OFFICE.

LOUIS A. SHEPARD, OF BROOKLYN, NEW YORK, ASSIGNOR TO CORNELIUS VANDERBILT, OF NEW YORK, N. Y.

CENTER-PLATE FOR RAILWAY-CARS.

SPECIFICATION forming part of Letters Patent No. 729,967, dated June 2, 1903.

Application filed October 10, 1902. Serial No. 126,728. (No model.)

To all whom it may concern:

Be it known that I, LOUIS A. SHEPARD, a citizen of the United States, residing in the borough of Brooklyn, city and State of New York, have invented certain new and useful Improvements in Center-Plates for Railway-Cars, of which the following is a full and true description, reference being had to the accompanying drawings, showing an embodiment of my improvements.

One object of my invention is to provide a new and simple form of center-plate for the bolsters of car-bodies. A second object is to combine such center-plate with the center sills 15 of the car, so as to have a structure of great strength.

Referring to the accompanying drawings, Figure 1 is a top view of the improved center-plate devised by me, and Fig. 2 is a longitudinal section of such center-plate. Fig. 3 is a detail view showing the center sills of a car and one form of body-bolster with which my center-plate may be used; and Fig. 4 is a half-section between the bolster-beams of Fig. 3 and showing the connections between the center-plate and center sills, the bolster-beams, spacing side bearing, and the side sill of the car.

The drawings show certain features of body-bolster construction which are shown, described, and claimed in an application, Serial No. 103,533, filed by Cornelius Vanderbilt, April 18, 1902. Such features form no part of my invention, which is defined by the appended claims.

The center-plate which I have devised is preferably made of one piece of metal, and a casting will usually be employed for this purpose. As shown, the center-plate is box-shaped and comprises a base 1, a centrally-located bolt-opening 3, an annular wall 2, rising to said opening, end walls 4, side walls 5, side flanges 6, and strengthening-ribs 7 and 8. The base 1, as shown, may be a concentric dish-shaped part, and the strengthening-ribs 7 and 8 may extend, as shown in Fig. 2, from the upper edges of the walls 4 and 5 to the upper edges of the annular wall 2 and downwardly to the bottom of the dish-shaped part constituting the base 1. The side walls 5 are provided with a plurality of vertical strengthening-

ribs 11 and with openings 10 for the passage of bolts or rivets.

The center-plate is secured, as hereinafter described, to center sills or other parts of the frame or body of the car. Outwardly-extending bosses on the exterior of the side walls 5 surround the openings 10 and strengthen such side walls.

It will be obvious that the center-plate described may be secured in various ways to the car-body or car-frame. I prefer, however, that it shall be secured between the center sills, which latter for economy and strength may be parallel channel-beams running from end to end of the frame.

Referring now to Figs. 3 and 4, showing details of the construction at the junction of the center sills, body-bolsters, and center-plate, 12 12 indicate the center sills, each of which may be a channel-beam running throughout the length of the car. 13 13 indicate the side walls of the car, and 19 the uprights which support the hopper or other car-body.

The center-plate, as shown in Fig. 4, is secured between the center sills by means of rivets. These pass through openings 10 of the side walls 5 of the center-plate. The bottom flanges of the beams 12 rest upon the side flanges 6 of the center-plate. The top flanges of the center sills 12 support cross-beams 20, and the structure is further braced by angle-bars or channels 17, which are riveted to the center sills and beams 20. The floor-brace or cover-plate 18 is laid upon and secured to the beams 20, all substantially as described in the aforesaid application.

Each of the body-bolsters may comprise a pair of metal plates 14, preferably parallel with each other, secured at the upper edges by rivets to cross-beams 20, connected at their outer ends by angle-irons 21 to side sills 22 and connected at their inner ends by large angle-irons 16 to the center sills 12. About midway between the angles 21 and the angles 16 the plates 14 are braced and spaced apart by an inserted device. For this purpose a casting 15 may be employed, which constitutes a side bearing having a downwardly-extending bearing part and upwardly-extending side and cross ribs, the former being in

contact with the inner sides of the plates 14 and secured thereto by rivets.

I do not desire to be understood as limiting my invention to the form of center-plate described and shown, but include all such modifications thereof as will readily suggest themselves to persons skilled in the art.

What I claim is—

1. A metallic center-plate, comprising a web-like base having a raised center portion, a depressed intermediate portion, and a raised outer portion, and upstanding walls rising from said outer portion and forming a box-like structure, substantially as described.
- 15 2. A metallic center-plate, comprising a web-like base, having a raised center portion, a depressed intermediate portion, and a raised outer portion, upstanding side walls rising from said outer portion and laterally-extending flanges below the tops of said walls, substantially as described.

- 25 3. A metallic center-plate comprising a web-like base having a raised center portion, a depressed intermediate portion, and a raised outer portion, upstanding side walls rising from said outer portion and laterally-extend-

ing flanges at the base of said walls, substantially as described.

4. A metallic center-plate, comprising a web-like base, having a raised center portion, 30 a depressed intermediate portion and a raised outer portion, upstanding walls rising from said outer portion and strengthening-ribs integral with said walls and base, substantially as described.

35 5. A metallic center-plate, comprising a web-like base, having a raised center portion, a depressed intermediate portion and a raised outer portion, upstanding walls rising from said outer portion, said walls having exterior 40 strengthening-ribs, substantially as described.

6. In a car, a center-plate having a horizontal rotary bearing-surface, upstanding side walls, and laterally-extending flanges, in combination with center sills engaging the said 45 walls and flanges, substantially as described.

In witness whereof I have hereunto signed my name this 9th day of October, 1902.

LOUIS A. SHEPARD.

In presence of—

WILLIAM K. AUCHINCLOSS,
JAMES J. COSGROVE.
